UNITED STATES PATENT OFFICE.

WILLIAM R. ALLEN AND THOMAS K. MCREA, OF GLACIER, WASHINGTON; SAID MCREA
ASSIGNOR TO SAID ALLEN.

SPAR-TREE PROTECTOR AND FASTENING DEVICE FOR HIGH-LEAD BLOCKS.

1,423,292.

Specification of Letters Patent. Patented July 18, 1922.

Application filed July 18, 1921. Serial No. 485,778.

To all whom it may concern:

Be it known that we, WILLIAM R. ALLEN and THOMAS K. MCREA, citizens of the United States, residing at Glacier, in the 5 county of Whatcom and State of Washington, have invented a new and useful Spar-Tree Protector and Fastening Device for High-Lead Blocks, of which the following is a specification.

10 Our invention relates to improvements in high-lead block fastening and protecting devices for spar trees used in high-lead logging, and the objects of our improvements are to provide a simple and safe fastening 15 and protecting device, to separate the device into two parts which can closely fit trees of different diameters and make installation easier, and to fasten the strain and guy members in a manner to cause the separate 20 parts of the protecting device to be drawn against the tree.

We attain these objects with the device illustrated in the accompanying sheet of drawings in which Figure 1 is a plan view 25 of a spar tree with our device in place, Fig. 2 is a front elevation of Fig. 1 and Fig. 3 is a side elevation of Fig. 1.

Similar characters refer to similar parts throughout.

30 More particularly: A is the top part of the spar tree.

4, 4 are two similar curved sheets of boiler plate formed to fit the spar tree with a space between opposite edges of the plates.

35 5 is a saddle plate spiked to the top of the spar tree.

6, 6 are ears fastened on the upper ends of the middle of plates 4 with which is engaged cable 7 over saddle plate 5 for sup-

40 porting the plates.

8, 8 are ears on back plate 4 to which are fastened guy cables 10.

9, 9 are ears on front plate 4 to which are fastened guy cables 11.

45 12, 12 and 12, 12 are two pairs of ears fastened to the edges of plates 4, each of which is provided with a ring 13. Each pair of rings 13 is engaged with a clevis connected to one of the two guy cables 14.

50 15, 15 are two ears, each fastened to an edge of back plate 4.

To each of ears 15 is fastened a curved link 16, the two constituting a pair, the eyes

in the lower ends of which are engaged with clevis 17, which is connected to high-lead 55 block 18, in which is riven line cable 19.

20, 20 are two ears fastened to the edges of front plate 4.

To each of ears 20 is fastened a curved link 21, constituting a pair the lower eyes of 60 which are engaged by clevis 22 connected to high-lead block 23, in which is riven cable 24.

In high-lead logging in the northwest the spar trees are subjected to very heavy 65 strains. As usually rigged, they are also exposed to attrition from the heavy blocks and moving cables which they support. These destructive forces sometimes operate to weaken the tree to a degree which unfit 70 it for the great strains which it must bear and it breaks, allowing the rigging to fall, causing loss to the operator and, not infrequently, the loss of lives of operatives.

Hitherto devices have been offered to provide the spar trees with protection, but, as understood, they either have been ineffective or so heavy and poorly designed as to be well nigh impossible to install.

In our improvements we have had in mind 80 a structure as light as the heavy duty makes safe, and a design that will permit its easy installation and provide for a distribution and direction of the operative strains which will aid in retaining it in place.

Although the limitations of the drawings suggest a smaller distance, we prefer to locate the top of plates 4 about six feet below the top of the tree. In erecting, a block 90 is fastened on the top, and a cable riven therein affords a ready means of hoisting the protecting plates to their operative places. With these plates properly installed on supporting cable 7 the mounting of the rigging is an easy matter.

95 By dividing the protecting plates in two, their installation as stated is made possible, their adaptability to varying sizes of trees is assured, and the portability of the rig is favored; while our method of using these 100 protecting plates for attachment purposes also, in the manner shown, not only retains these plates in their operative position but distributes the pressures of the operative strains over wide areas of the spar tree 105 without injury thereto.

Attention is directed to the two methods of causing guying and high-lead strains to more firmly seat the plates in place.

Guys 14, 14 retain the spar tree erect laterally. Each is fastened to both of plates 4 by means of a clevis through two rings, each in an ear on one of said plates. Opposing strains on cables 14 thus tend to draw plates 4 together.

10 Guys 11, 11 resist the line strains on block 18. Said guys are fastened to front plate 4, while block 18 is fastened to ears 15, 15 on back plate 4. Thus line strains on cable 19 tend to force plates 4 together.

15 Guys 10, 10 resist the line strains on block 23. Said guys are fastened to back plate 4 while said block is fastened to ears 20, 20 on front plate 4. Thus also line strains on cable 24 tend to draw plates 4 toward each 20 other.

It is, of course, understood that the top only of the spar tree and its rigging are shown in the drawings, and that guys 10, 11 and 14 are each anchored to the ground and 25 each is provided with a pair of blocks in line, or a winch, for making and keeping them taut.

Having thus fully disclosed our invention, what we claim as new and desire to secure 30 by Letters Patent is,—

1. In combination, a spar tree, a pair of curved plates mounted on opposite sides of said tree and not entirely surrounding said tree, and a high-lead block fastened on one 35 side of said tree to the plate on the opposite side of said tree from said block and adapted to bear on the plate adjacent to said block when not under operative strain.

2. In combination, a spar tree, a pair of 40 curved plates mounted on said tree and not entirely surrounding said tree, a pair of

high-lead blocks, each fastened to the plate on the opposite side of said tree from said block and adapted to bear on the plate adjacent to said block when not under oper- 45 ative strain.

3. In combination, a spar tree, a pair of curved plates mounted on opposite sides of said tree but not entirely surrounding said tree, a plurality of guy wires fastened to 50 the ground and to said plates adapted to cause said plates to approach each other and bear against said tree, and a pair of high-lead blocks each fastened to the one of said plates which is on the other side of said 55 tree from said block.

4. In combination, a spar tree, a saddle plate mounted on top of said tree, a pair of curved plates mounted on opposite sides of said tree and not entirely surrounding the 60 same, a supporting cable bearing on said saddle plate and having each end fastened to one of said curved plates, two pairs of adjacent ears, one of said pairs of ears fastened on each of the adjacent edges of said 65 curved plates, a ring in each of said ears, a shackle engaged with each pair of said adjacent rings, a pair of oppositely-pulling guy wires each fastened to the ground and to one of said shackles, twin guy wires fastened to the ground and to the opposite edges of one of said plates adapted to cause 70 said plate to bear against said tree, twin guy wires fastened to the ground and to opposite edges of the other of said plates 75 adapted to cause said plate to bear against said tree, and a pair of high-lead blocks on opposite sides of said tree, each fastened to one of said plates on the opposite side of said tree from said block.

WILLIAM R. ALLEN.
THOMAS K. McREA.
